Des. 196,747
Patented Oct. 29, 1963

196,747

SLIDING LATCH OR SIMILAR ARTICLE

George Kopf, Brooklyn, N.Y., assignor to Porta
Aluminum, Inc., Old Bethpage, N.Y.

Filed Mar. 28, 1963, Ser. No. 74,174

Term of patent 14 years

(Cl. D50—5)

Fig. 1

Fig. 2

Fig. 3

Fig. 4

Fig. 5

Fig. 6

Fig. 7

FIGURE 1 is a perspective view of a sliding latch or similar article, showing my new design;

FIGURE 2 is a side elevational view thereof;

FIGURE 3 is a view in elevation showing the side opposite that seen in FIGURE 2;

FIGURE 4 is a view in elevation as seen from the left-hand portion of FIGURE 2;

FIGURE 5 is a view in elevation showing the side opposite that seen in FIGURE 4;

FIGURE 6 is a bottom plan view; and

FIGURE 7 is a top plan view.

I claim:

The ornamental design for a sliding latch or similar article, substantially as shown.
